Whittlesey & Wright,

UNITED STATES PATENT OFFICE.

ADAM SCHUNCK, OF CELINA, OHIO.

HARNESS.

SPECIFICATION forming part of Letters Patent No. 401,973, dated April 23, 1889.

Application filed January 30, 1889. Serial No. 298,106. (No model.)

To all whom it may concern:

Be it known that I, ADAM SCHUNCK, a citizen of the United States, residing at Celina, in the county of Mercer and State of Ohio, 5 have invented certain new and useful Improvements in Harness; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to gig-saddles, and has for its object improvements in their construction. The first relates to the pad and the second to the manner in which the terrets are secured and firmly retained in their 20 proper position.

In the construction of the pad I dispense with the usual objectionable stuffing material, which absorbs perspiration from the horse, as the pads do as usually constructed. This 25 I consider an important feature of my invention, as in time the cover wears through on the under side, and the stuffing material becomes exposed, which is very liable, in case of a sore back, to communicate poisonous matter to the horse. Again, the moisture which the stuffing material retains causes the destruction of the pad within a short time.

In the accompanying drawings, Figure 1 is a front view of my gig-saddle. Fig. 2 is a side 35 elevation of the same. Fig. 3 is a transverse section of the pad on line $x'y$ in Fig. 1. Fig. 4 is a longitudinal section of a portion of the pad, taken on the line $z'z$, Fig. 3. Fig. 5 is a transverse section of the pad, taken at the terret-ring, and Fig. 6 is a longitudinal section 40 of a portion of the pad at the terret-ring.

In the drawings like letters of reference indicate corresponding parts in all the figures.

A represents a gig-saddle having a pad, a , 45 constructed in accordance with my invention, the same having the usual curve to fit the back of a horse, and provided with the usual back-bands, a^2 a^3 . It is of the usual length and width, and is secured to the saddle-plate B in 50 the ordinary manner. The increased thick-

ness of the pad at a is not due to the use of any stuffing material, but to the usual plate and leather cover for retaining the terret-burr in proper position. This construction will be fully explained hereinafter.

55

The pad a is constructed in the manner shown in Figs. 3 and 4. A piece of leather of suitable length and width, C, usually called a "filling," is covered with coarse textile material or bagging D, the edges of which meet 60 or nearly so along the center line of the filling on the outside. Then around this strip, composed of the filling and bagging, is wrapped in a similar manner a facing-strip, E, the edges of which meet at the center on the outside, as 65 shown at e . These parts—the filling, bagging, and facing-strips—are securely held in the position indicated, and on the top of the same is placed the flap F. This is secured to the other portions of the pad by stitching f , as shown 70 in Figs. 2 and 3. The sides of the pad are rounded up by tooling, as shown in Figs. 3 and 5, which obviates any danger of the edges injuring the horse's back. It will be seen from the construction of the pad that it omits the 75 objectionable rattans, which frequently break and work out, rendering repairs necessary.

It will be further noticed that all the parts composing the pad are held together by the two lines of stitching, as indicated in Figs. 2 80 and 5 by f , and which is the only fastening required.

The improved manner in which the terret-burrs are secured and prevented from turning inside of the pad is shown in Figs. 5 and 6. 85

The terret burr or nut G is of an oblong shape, and is let into a recess provided on the under side of usual plate, H. The terret-burr is retained in this recess by means of a leather cover, I, which is sewed to the plate H, the 90 thread passing through openings in each side of the terret-burr, as shown by the dotted lines i .

Instead of the terret-burr being retained in the manner described, it might be preferable 95 to secure it to the plate H by rivets passing through holes provided in both, as shown at i , and dispensing with the leather cover for the terret-plate and the sewing, as described.

It will be seen that if either method is fol- 100

allowed the terret-burr G will be retained in its position in relation to the plate H, and the terret-rings K will always remain in fair position for the reins to pass through them, and will maintain the saddle-pad a firmly in contact with saddle-plate B, thus always preserving its proper contour.

Having fully described my invention, what I claim as new, and desire to secure by Letters

Patent, is—

In a harness-pad, the flat leather strip or filling C, the coarse textile material or bag-

ging D enveloping the same, the facing-strip E, surrounding the filling and the bagging, the edges of which meet on the center line on the outside, and the facing-strip secured to the other parts by two rows of stitching, substantially as described.

In testimony whereof I affix my signature in the presence of two witnesses.

ADAM SCHUNCK.
